UNITED STATES PATENT OFFICE

2,584,651

LOW-PRESSURE STEAM GENERATING SYSTEM

Eugene Porter Worthen, Braintree, and Benjamin Fox, Wollaston, Mass., assignors to Bethlehem Steel Company, a corporation of Pennsylvania

Application October 4, 1946, Serial No. 701,224

5 Claims. (Cl. 60--95)

1

This invention relates in general to a system for generating low pressure steam, and more particularly to an auxiliary low pressure steam system especially adapted for marine use and completely isolated from the high pressure steam system.

The increasing use on modern ships of very high steam pressures, in the neighborhood of 1500 pounds or more per square inch, is attributable to the marked advantages in thermal efficiency, fuel economy and speed when such pressures are applied to main propulsion; but high pressures are obviously unsuitable for most auxiliary purposes, such as supplying steam for various heating services or for deck machinery. Large passenger vessels, for instance, require large amounts of low pressure steam for heating and galley purposes. Other special types of vessels, such as oil tankers, which cannot use electrically driven deck auxiliaries with safety because of the fire hazard, must operate such auxiliaries as mooring winches, hatch cover winches, and anchor windlasses with low pressure steam. The exhaust steam from equipment of this type may carry large quantities of lubricating oil and grease which must be prevented from entering the main boiler feed system, and steam drains from fuel oil heaters and other heating services may also be contaminated, so that a low pressure steam system safely and completely isolated from the main steam system is necessary.

While such systems can be supplied with steam by means of one or more auxiliary Scotch boilers, the complications of additional operating personnel and numerous expensive items of equipment such as fuel-oil pumps, burners, extra piping, forced-draft blower and uptakes, all of which can be omitted with a closed evaporator system, render our invention much more economical and simple than the Scotch boilers.

One object of our invention, therefore, is to provide a low pressure auxiliary steam system adapted for marine use and completely isolated from the main propulsion steam system.

Another object is a low pressure steam generating system characterized by simplicity and low cost as compared with a separately fired steam generating unit.

Another object is a low pressure steam system provided with automatic pressure regulating valves and level controllers and requiring a minimum of attention by the operating force.

A further object is a low pressure steam generator having a large water storage capacity and thereby able to meet sudden demands for steam

2

in excess of rated capacity with very slight drop in steam pressure.

Still another object is a low pressure steam system characterized by very low maintenance charges and a minimum of effect on the propulsion cycle.

Other objects, purposes and advantages of the invention will appear hereinafter in the specification and in the appended claims, and in order to render the same more clear we shall now refer to the annexed two sheets of drawings in which like characters of reference indicate like parts:

Fig. 1 is a diagrammatic view of the combined high and low pressure systems;

Fig. 2 is a diagrammatic view of the low pressure steam generating system alone;

Fig. 3 is a longitudinal sectional view of the low-pressure steam generator;

Fig. 4 is a top plan view of the drain cooler, with inner and outer shells partly broken away to show the tubes;

Fig. 5 is a transverse sectional view taken on the line 5—5 of Fig. 4 across the feed inlet and outlet connections of the drain cooler;

Fig. 6 is a transverse sectional view taken on the line 6—6 of Fig. 4;

Fig. 7 is a transverse sectional view taken on the line 7—7 across the side inlet connection of the drain cooler for admitting drains from the low-pressure steam generator; and

Fig. 8 is an end view of the drain cooler with the end cover plate removed.

Referring now to the diagrams, the piping system for high pressure steam is shown in heavy solid lines, that for high pressure condensate in heavy dashed lines, that for low pressure steam in light solid lines, and that for low-pressure condensate in light dashed lines, the direction of flow in each case being indicated by the arrows.

As shown in Fig. 1, the high pressure steam (about 1450 pounds per square inch) generated in the drum boiler 1 flows through the superheater 2 and conduits 3, 4, 5 and 6 to supply directly the high pressure propulsion turbine 7, the re-heaters 8 and 9 and the turbo-generator 10, and through the conduit 11 the main feed pump 12. Because of the high saturation temperature of the steam, and to obtain minimum gas outlet temperatures and optimum efficiency, an air heater 13 and a feed water economizer 14 in the boiler 1 using the flue gases for heating are provided. A desuperheater 15 located below the water level in the drum boiler 1 and drawing boiler steam through the conduit 16 supplies a 50 400 pounds per square inch auxiliary steam line

17 via the conduit 18 and the pressure-reducing or throttle valve 19.

From the high pressure turbine 7, the propulsion steam passes through the bleeder connecting line 20, the high-pressure steam reheat 8, the intermediate pressure turbine 21, the bleeder connecting line 22, the low-pressure steam reheat 9 and the low pressure turbine 23 to the main condenser 24. Reheater drains are pumped by motor-driven drain pumps 25 and 26 through conduits 27 and 28 back to the boiler 1. Drains from the turbo-generator 10 pass to the auxiliary condenser 29.

The condensate and low-pressure feed system includes a first-stage combination feed heating unit of the type described in the United States patent to E. P. Worthen, No. 2,328,044, issued August 31, 1943; a feed water drain collecting tank 30, and a second stage deaerating feed heater 31.

The above-mentioned first-stage feed heating unit is a closed type unit combining within one shell the auxiliary air ejector intercondenser 32, the main air ejector intercondenser 33, the feed heater drain cooler 34, the combined gland exhaust condenser and main and auxiliary air ejector aftercondenser section 35, and the first stage feed heater section 36, which are arranged in the shell from bottom to top in the order named.

The combined first stage unit receives the separate condensates pumped from the main and auxiliary condensers 24 and 29 by motor driven pumps 37 and 38 through conduits 39 and 40; and discharges the combined heated condensates to the second stage deaerating feed heater 31. The main condensate flows through the tube passes of the main air ejector intercondenser 33 and the feed heater drain cooler 34, while the auxiliary condensate flows through the auxiliary air ejector intercondenser 32 and combines with the main condensate at the entrance to the combined main and auxiliary air ejector aftercondenser and gland exhaust condenser section 35. The total condensate then flows through the passes of that section and the first stage feed heater section 36.

Heating steam conducted from the low-pressure turbine bleeder 41 through the conduit 42 is directed across the tubes in said feed heater section 36. The drains therefrom pass through conduit 43, traverse the drain cooler 34, and discharge through conduits 44 and 45 with additional make-up feed to the main condenser 24.

For distilling fresh water from sea water there is provided a single effect evaporator unit 46 of the type shown in the United States patent to Worthen and Fox, No. 2,378,350, issued June 12, 1945. Heating steam from the low-pressure turbine bleeder 41 is supplied through the conduit 47 to tubes in the evaporating section 48, draining through the conduit 49 to the auxiliary condenser 29. Steam from the 400 pound line 17 is further reduced in pressure by the reducing valve 50, and is supplied through the conduits 51, 52, 53, 54, 55, 56 and 57 to the air ejector jets 58, 59, 60 and 61. Drains from the main and auxiliary air intercondensers 33 and 32 pass through the conduits 62 and 63 to the main and auxiliary condensers 24 and 29.

Exhaust steam from the turbine and turbo-generator glands 64, 65, 66 and 67 is conducted by means of conduits 68 and 69 and 70 to the gland exhaust condenser 35. Drains from the gland exhaust condenser 35 and from the air-ejector condenser 71 of the evaporator 46 pass

through conduits 72 and 73 to the feed water drain collecting tank 30, the outlet of which connects to conduit 45 and main condenser 24.

Feed from the first stage feed heater 36 is conducted through the conduit 74 and vent condenser section 75 to the second stage deaerating feed heater 31, which is heated by steam taken from the bleeder connecting line 22 between the outlet of the intermediate pressure turbine 21 and the inlet of the low pressure reheat 9 by the conduit 76.

The turbine-driven feed pump 12 draws feed from the second stage feed heater 31 through the conduit 77 and discharges it through the conduit 78 to the two succeeding stages of high pressure feed heating, which receive the feed pump discharge at about 245° F. and discharge the heated feed at about 380° F. to the economizer 14.

The third and fourth stage feed heaters 79 and 80, which comprise the high pressure feed heating system, are connected in series by the conduit 81 and discharge through the conduit 82 to the economizer 14 as aforesaid. Heating steam for the third stage feed heater 79 is taken through the conduit 83 from the intermediate-pressure turbine bleeder 84, and for the fourth stage feed heater 80 is taken from between the outlet of the high pressure turbine 7 and the high pressure reheat 8 by the conduit 85.

Both the third and the fourth stage feed heaters 79 and 80 are provided with integral drain coolers 86 and 87. Fourth stage feed heater drains discharge through the conduit 88 to the third stage feed heater 79, and the total drains from both these feed heaters discharge through the conduit 89 to the second stage feed heater 31.

A portion of the relatively cold water (about 245° F.) from the discharge of the feed pump 12 is introduced through the conduit 90 into the throttle bushings of the reheat drain pumps 25 and 26 and returned through the conduit 91 to the second stage feed heater 31. This serves to lubricate the bushings as well as to prevent the erosion which would occur if the reheat drains were permitted to flash through.

The 125 pounds per square inch auxiliary system shown in Fig. 2 supplies motive steam to all steam driven deck auxiliaries and in addition furnishes heating steam to fuel oil heaters, galley, and ship's heating system, which for convenience may be grouped together as the steam consumers 92. As shown, the system comprises a low pressure steam generator 93, a drain cooler 94, and a combined atmospheric condenser, contaminated drain inspection tank and hotwell 95, together with the associated feed pumps 96 and 97, pressure regulators 98 and 99, and float level controllers 100 and 101.

As shown in Fig. 3, the low pressure steam generator 93 is primarily a horizontal submerged tube evaporator or steam transformer of large capacity, enclosed within a steel container shell which comprises the cylindrical casing 102, the front head 103 having a cylindrical nozzle opening 104, and the rear head 105. The inlet-outlet head 106 is provided with a vent 107 and with a horizontal wall 108 which together with the front tube sheet 109 forms the inlet 110 and the outlet 111. An upper nest of tubes 112 and a lower nest of tubes 113 extend from the front tube sheet 109 to the rear tube sheet 114, and are supported intermediate the ends by a tube support plate 115 secured to an upper baffle plate 116 which connects said tube sheets 109 and 114. A cover head 116 together with the rear tube sheet 114 forms a

chamber 117 with which the rear ends of all the tubes communicate. The lower nest of tubes 113 is sloped downwardly toward the outlet end to facilitate the discharge of condensates. A low pressure steam outlet 118 connected to the dry pipe 119, surface and bottom blow-off pipes 120 and 121, a perforated feed distributing pipe 122 located beneath the tube nest 113, a flange connection 123 for a relief valve 123', and an access manhole 124 are also provided.

As shown diagrammatically in Fig. 2, heating steam may be supplied to the inlet 110 of the steam generator 93 from either the 400 pounds per square inch auxiliary line 17 through the conduit 125 for operation in port when the deck machinery load is large, or through the conduit 126 from the high pressure turbine bleeder line 85 at approximately 185 pounds per square inch pressure at sea when the load consists largely of fuel oil heating and steam heating.

Steam from either source is controlled by the pressure-regulating valves 98 or 99 having pressure-governing lines 127 and 128 connected to the shell of the steam generator 93. These valves admit sufficient steam to the tube nests 112 and 113 under varying conditions to maintain the shell pressure substantially constant at 125 pounds per square inch. In addition steam from the 400 pound auxiliary steam line 17 is automatically supplied to the tube nests 112 and 113 through a cross-connected reducing valve 129 at 125 pounds per square inch at times when the unit is operating on the high pressure turbine bleeder line 85 and on account of reduction of power the bleeder pressure falls below 125 pounds per square inch. This adds to stability by maintaining a supply of auxiliary steam at approximately 100 pounds per square inch pressure for fuel oil heating and steam heating under all conditions and is especially useful during maneuvering when the bleeder pressure may drop below 125 pounds per square inch.

Tube nest drains are discharged through the conduit 130 to the drain cooler 94, which also serves as a feed heater for heating the feed going to the steam generator 93.

The steam generator tube nest drain cooler 94 may be mounted on the base of the steam generator 93, and is a multi-pass unit with enclosing steel shells 94a and 94b and arranged for counterflow with the tube nest drains inside and the steam generator feed outside the tubes 94c. External connections are made through the waterchest 94d. The drains from the low-pressure steam generator thus enter the drain inlet 94e make two passes through the tubes 94c, and exit through the drain outlet 94f, while feed entering the feed inlet 94g is directed across the tubes counterflow to the drains by means of the internal division baffle plates 94h and leave through feed outlet 94i. A level is maintained in the drain pipe 130 from the steam generator 93 to the drain cooler 94 by means of the float control 100 actuating the drain regulating valve 131 which controls the drains discharging from the drain cooler 94 through the conduit 132 to the second stage deaerating feed heater 31 in the main feed system. The high pressure steam and drains are thus completely isolated from the low pressure 125 pounds per square inch system.

The primary function of the drain cooler 94 is to cool the drains before they discharge to the deaerating feed heater 31, thereby reducing the amount of flash vapor released by the drains as they are reduced to the temperature and pres-

sure of that unit. Under port conditions, when the load on the steam generator 93 is heavy and the load on the deaerating feed heater 31 is light, there is a possibility of excess flash vapor from the drains causing the relief valve of said deaerating feed heater 31 to blow. To remedy this condition, a by-pass line 133 is provided for by-passing steam generator feed to the atmospheric condenser 95, thereby cooling the drains still further and reducing the flash to a quantity which the deaerating feed heater 31 can handle.

The combined atmospheric condenser and hotwell 95 receives through the conduits 134 and 135 the exhaust from the deck auxiliaries and the contaminated drains from the heating services. It comprises a two-pass surface condenser 136 cooled with circulating water from the service main and having a vent 137 to atmosphere and mounted over a combined contaminated drain inspection tank 138 and hotwell 139. The inspection tank 138 is equipped with an inspection port light 140, a scum pan drain 141, baffles 142 and a weir 143 discharging to the reservoir or hotwell 139.

Two feed pumps are provided in parallel in the low pressure system, one the small capacity electric feed pump 96 for use at sea, and the other the steam-driven double-acting duplex feed pump 97 of large capacity for use in port. The feed pumps take suction from the hotwell 139 of the combined atmospheric condenser 95 through the conduit 144 and discharge through the conduit 145 and the drain cooler 94 to the feed distributing pipe 122 in the steam generator shell. Steam to operate the steam-driven feed pump 97 is taken from the 125 pound steam generator 93 itself. The water level in the steam generator shell is maintained by the float level controller 101 which operates a by-pass valve 146 to the pump discharge line 145 to by-pass excess feed back to the atmospheric condenser 95, and which also operates a throttle valve 147 in the steam supply line 148 to the steam feed pump 97. Make-up feed is supplied to the inspection tank 138 through the valve 149 from the fresh water drain tank 30.

From the foregoing description it will be understood that our invention may be regarded as having two distinct aspects: as an isolated low pressure steam generating system, complete in itself and employing an evaporator, drain cooler, atmospheric condenser and automatic controls; or as it is fitted into the ship's main cycle, from which the heating steam is taken and to which the cooled drains are returned with a minimum of disturbing effect.

The system is applicable to any size of ship and in any capacity of steam output which may be required.

Although we have described our invention hereinabove in considerable detail, we wish it to be understood that the present disclosure is illustrative, rather than restrictive, and that modifications, substitutions and equivalents may be resorted to without departing from the spirit or scope of the appended claims.

In accordance with statute, we claim the following as our invention:

1. A low pressure steam generating system comprising a high pressure steam operated prime mover, an evaporator receiving steam exhausted from said prime mover and having means for condensing said steam and for evaporating water thereby, an auxiliary source of intermediate steam pressure, and a reducing valve connected

thereto and arranged to supply supplemental steam to the evaporator when the pressure of the exhaust steam from the prime mover falls below a predetermined level.

2. A steam generating system comprising a steam operated prime mover, an evaporator receiving steam exhausted from said prime mover and having means for condensing said steam and for evaporating water thereby, means responsive to the pressure within the evaporator for controlling the admission of steam to maintain such pressure substantially constant, a drain cooler cooling the drains from the evaporator, a condenser receiving and condensing the exhaust, and pumps forcing the condensate from the condenser to the drain cooler to cool the evaporator drains.

3. The combination with a high pressure boiler and a turbine connected to receive steam therefrom, of a low pressure steam generator connected to receive heating steam from said turbine, a drain cooler connected to receive drains from said steam generator and to return them to the high pressure boiler feed, steam consumers connected to receive and utilize low pressure steam from the steam generator, condensing means connected to receive the exhaust from the steam consumers, an inspection tank and hotwell connected to receive and store condensate therefrom, pumping means connected to force feed from the hotwell through the drain cooler to the steam generator, and means for controlling the pumping means in response to the level of liquid in the steam generator.

4. The combination with a high pressure boiler receiving feed from a deaerating feed heater, of a low pressure steam generator having tube nests in an enclosing shell and evaporating water within the shell to low pressure steam by means of high pressure steam circulated through the tube nests, a plurality of steam consumers re-

ceiving said low pressure steam, a drain cooler receiving the drains from the steam generator and heating the feed going to the steam generator, a level controller regulating the discharge of the drains to the deaerating feed heater, a combined condenser and hotwell receiving exhaust from the steam consumers, and pumping means withdrawing feed from the hotwell and discharging the feed through the drain cooler to the steam generator.

5. The combination with a high pressure boiler and a pressure reducing valve connected to deliver steam therefrom, of a low pressure steam generator connected to receive heating steam from said valve, a drain cooler connected to receive drains from said steam generator and to return the same to boiler feed, steam consumers connected to utilize low pressure steam from the steam generator, condensing and reservoir means connected to the steam consumers, pumping means connected to force feed therefrom through the drain cooler to the steam generator, means for by-passing a portion of the feed back to the condensing means, and automatic means for controlling the amount of feed by-passed in response to the level of feed in the steam generator.
